SANDWICH SERVER

George W. Bergauer, 945 Marias Drive,
Bellefontaine Neighbors, Mo.

Filed Dec. 5, 1962, Ser. No. 72,736

Term of patent 14 years

(Cl. D44—10)

FIG. 1 is a top plan view of the sandwich server showing my new design;

FIG. 2 is a side elevational view thereof;

FIG. 3 is a longitudinal sectional view taken at line 3—3 in FIG. 1;

FIG. 4 is a transverse sectional view taken at line 4—4 in FIG. 1; and

FIG. 5 is a fragmentary sectional view taken at line 5—5 in FIG. 1.

I claim:

The ornamental design for a sandwich server, substantially as shown.
